UNITED STATES PATENT OFFICE.

WILLIAM PATRICK HENRY, OF NEW YORK, N. Y.

BOTTLE CLOSURE AND METHOD OF MAKING SAME.

Application filed September 1, 1926. Serial No. 132,856.

This invention relates to stoppers for bottles, and particularly complete closures for sealing and protecting the mouth of bottles, especially in a class of which at present the 5 milk and cream bottle top protection are of greatest importance. While applicable to other cases, the specific form or forms of construction of the article shown or described hereinafter, involve the closing of such 10 bottles plus the protection of the lip of the bottle for sanitary purposes as well as the various other advantages well recognized and desired to gain, and for the accomplishment of which devices in the past have not 15 been successful to the extent of providing practical devices at low cost of production, nor devices that would accomplish the desired results for various reasons, as herein-after described.

20 While my invention may be practiced in various ways, and the production of the article is susceptible of modifications depending upon the facilities for manufacture and the particular design of closure desired, 25 the following specification describes a particular embodiment with certain modifications, of an article particularly suitable for the combined operation of sealing and protecting the top of the milk, cream, or like, 30 bottle.

This particular embodiment involves marked economy in production compared to the products heretofore attempted. It provides an article which may be applied by 35 machine, but also by hand, to close and protect milk bottle tops, and to effect this closure with economy by hand as well as machine, and, when by hand it is done sanitarily. The methods of forming the device 40 may be varied, and in this application a general method of production is described with the understanding that those skilled in the art of automatic machinery and the manipulation of paper, or other suitable 45 materials, may provide apparatus for quantity production with increased economy.

In particular, the article comprises a disc, generally as described in the Barnhart patent of September 17, 1889, to which I attach 50 a lip cover in a manner and of a form to be held to the lip of the bottle in a thoroughly practical and effective manner. The attachment of the lip cover in no way interferes 55 with the effectiveness of the securing of the disc or cap forming the content seal, but

augments the security of that seal and in addition provides a complete closure by the addition of a lip cover secured to the disc and snugly fitting over the lip of the bottle, and it provides this with a cover portion 60 having an inextensible maximum diameter or peripheral border with the advantages as herein set forth. This border or skirt, which fits the outside surface of the bead of the bottle, is substantially inextensible, so 65 that the article as produced has an edge, and preferably a thin edge, which clings snugly to the outside surface of the bead of the bottle, and no softening by weathering or the application of ice on milk bottles, or change 70 in temperature, can then affect the snug fitting of the edge of the lip cover in the use of an article in this form. It will be understood that the original tensile strength of paper in the finished calendered product is 75 utilized to assure this advantageous fit and security in normal use. In the form of the radially inward curving portion of the cover, any excess of material is accommodated at a part of the closure structure where 80 a surplus in the form of folds, pleats or crimping, has no objectionable effect upon the advantages of the finished article. In addition, this cover production in combination with the cap, or disc closure, may be pro- 85 duced out of paper stock, as the preferred form of material, though other material may be employed, with the smallest possible waste or scrap. Thus, in the production of the cover portion, which is consolidated to 90 make the complete unit article, the blank may be a straight strip of paper, which in the method hereinafter described is formed into the finished article without any waste what- 95 soever,—a marked distinction from methods heretofore practiced involving the utilization of circular discs of paper, with substantial waste in production, simply folded over the top and sides of a bottle with additional waste of material in the folds. The 100 folds of such prior covers or hoods are furthermore a weakness at a point where weathering causes spreading that defects their proper functioning.

While I prefer to make my hood or cover 105 combined with the cap so that it will cover the lip portion of the bottle solely to the extent which is actually desirable or necessary for sanitary purposes, it may extend further down the bead, and with any change of 110

the standard form of bottle top, accommodations may be made without departing from my invention. The unit article, that is the combined cap and cover, has many advantages. In particular, it will be noted that when closing the bottles by hand, the outside surface of hood comes in contact with the fingers, and that part only, so that the undersurface of the cap which contacts with the contents is not subject to any contamination. Furthermore, the cap provides a secure hold, that is it holds tight in the bottle neck for all normal service, and by my securing of the advantageous form of cover or lip hood to the cap the entire article as a unit holds to the bottle and effects the protection as described, particularly on that part of the lip over which the milk flows when being poured out. With the short skirt of the hood the essential results are obtained, but without the edge of the cover extending to a position where the ordinary carrying of bottles would be liable to cause accidental dislodgment.

While the unit, cap and cover, as a complete article of manufacture serves admirably to meet the conditions of transportation, and the handling necessary for their attachment to bottles, it will be noted that the union of the cover with the top surface of the cap must have the formation which makes possible the proper application of the cap. Namely, if applied by hand, a plug must reach close to the rim of the cap, and, therefore, the hood relations to the cap must provide for this,—in order to uniformly and effectively seat the cap in order that the necessary holding position of the cap in the bottle or the neck is assured without injury to the cover. Likewise, the same condition must be met for machine capping, and in the detailed description herein the importance of these features will be noted.

While the complete unit is not alone the preferred form and embodies many advantages, it will be seen that the formation of a cover *per se* of the character and by the method herein described is in itself novel, and in some instances covers may be made with central discs for the purpose of their fitting for temporary use or otherwise without the locking cap as it provides the inextensible and snug fitting edge for protection.

I will now describe a particular form of embodiment of the invention suitable for present day purposes, understanding that machinery of various designs may be made for the most economical large production in view of the very large quantity of devices of this character necessary to supply daily requirements.

One particular embodiment of my invention with a method of forming the article is illustrated in the accompanying drawing, in which:

Fig. I is a top view of the finished cap and cover unit;

Fig. II is a cross section of a cap and cover, shown attached to the top of a milk bottle, also in section;

Fig. III is a cross section fragmentary view, on an enlarged scale, of a cap and cover at its junction with a bottle neck and cap seat;

Fig. IV is a cross section on the axis of forming dies for finishing the cap and cover unit;

Fig. V shows in cross section modified forming and finishing dies;

Fig. VI is a perspective view of a blank showing a first step in producing the cover; and,

Fig. VII is a perspective view showing a progressive formation in producing the cover.

The finished cap and cover A has the outside or skirt edge a continuous smooth inextensible border B, which is curved inward at C conforming to the bead 1 on the bottle, and turned at D to form a portion entering the interior of the bottle neck, with horizontal inwardly projecting portion E, which is folded or pressed to engage the flat top surface of the disc or stopper member F, known as a cap. Over the edges E, or folds as the case may be, a preferably opaque wafer G covers the top surface of the cap F as well as the inner edge E, which is secured around and near the periphery of the cap F. This wafer G is preferably the exact diameter of the reentrant or inner wall D of the cover but may extend upwardly along the cover portion, in which case it makes the article more waterproof. This wafer G is particularly adapted to carry the printing that is usual on the caps of milk bottles, to provide the necessary or desired designations, and when so used permits the printing in the most economical way instead of the necessity of printing on the finished article, which when finished is not flat. Printing may however be embodied as desired on other portions of the finished article. The wafer G is for finish and surface protection but not for holding strength on the inner neck wall.

While there are different ways in which this cap and cover, and particularly the cover portion, may be formed, the method preferably consists in winding a ribbon of paper A' into a circle so that one edge is the exact diameter of and therefore the length that will go around the bottle bead at the outer surface where the edge of the finished cover is intended to fit tight when applied. On the other edge of this ribbon of paper there may be slashes or notches a, a, to remove a surplus of that edge of the ribbon which afterwards is pressed into the flat radially inward projecting portion E, so

that it will lay flatter on the top surface of the cap, thus also saving material in the cutting of the tapes. This ribbon is suitably held at its lower edge, and the upper portion 5 is then bent, folded or crushed inwardly to form the pleated portion A². The quality of paper desired for these articles is readily folded in this manner and by suitable crimping machine, or otherwise, the uniformity 10 of product is provided.

The blank thus formed, as in Fig. VII, is placed between dies 2 and 3 to form the skirt, and 2' then forms the reentrant wall D and edge E, all of the exact ultimate configuration desired, and with the required 15 heat and moisture is pressed into the permanent cover form, ready for attachment to the cap portion F. The cover is then placed on the disc with one of the contacting surfaces suitably gummed, and the finished cap and cover will be produced as shown by the dies in Fig. IV. When a top wafer is desired, the wafer may be inserted at the same time, thus completely stamping or pressing 20 out the finished article. Preferably the finish forming of the cover portion is simultaneous with its attachment to the cap.

As shown in Fig. V, the die 2² may form only a portion of the curvature of the finished cover skirt, while a side die 4 is initially applied to the blank A' to hold the lower edge and at the same time form a small portion of the margin, and in this manner it permits crowding of the paper into 30 a small rib II, if desired, so as to have a circumferential strengthening of the skirt of the cover to aid in maintaining its formation. In the die shown in Fig. V there may also be a central plug 5, which in one 35 position forms the cover, but which can recede and permit a cap disc to be slid into the die so that a second press operation attaches the disc to the formed cover.

It will thus be noted that the formation of 45 the complete article as a cap and cover unit for milk bottles and the like comprises essentially the use of a ribbon of paper with a lap-joint, or two or more plies of thinner paper may be wound into the initial cylindrical formation, but in any case having the maximum diameter desired in the finished article; and the cupping of the cover into the desired shape results in the surplus paper forming folds, pleats or slashed projections on the radially inner portions of the cover, where they are unobjectionable. In the main, it provides an inextensible outer rim 50 to the skirt of the cover, which therefore assures the edge of the cover clinging to the glass at the outside of the bead and forming a perfect joint, for the required protection of the lip, both sanitary and otherwise. This assures the uniformity of fit of the cap and cover to the top of the 55 bottle and supplies the necessary overlap-

ping portion of the cover onto the top side of the cap disc in order to secure the two together and forms an hermetically sealed top with a recess in the cover just as sharp as required close to the periphery of the disc 70 or cap in order to accommodate the form of tool necessary to press the sealing disc or cap rim securely into its proper place on the shoulder in the neck of the bottle without breaking or distorting the cover. 75

While the device herein described, and the method of production in general, utilizes the tensile strength of paper as produced in the sheet, the inextensible edge of the hood or cover portion may be realized by the formation of the article from paper more in pulp form, or paper stock especially treated, as by heating and moisture, so that the cover portion may be provided by deformation of the paper structure. The apparatus or equipment therefore of necessity involves far greater initial expense, and the ultimate product will not have the predetermined tensile strength involved in the regular paper sheet production which has been finished and is necessarily seasoned, so that a definite assurance of rigidity of the outer lower edge of the skirt can be depended upon with its substantially inextensible periphery and without folds, fluting, or other configuration which has heretofore been involved in any attempts at making an article in this class. 90

When desired the inextensible edge of the sheet or fringe may be turned, rolled or given any desired strengthening formation without interfering with the close fit against the outer lip surface of the bottle, but I prefer that the thin edge terminate the bottom of the skirt adjacent to the usual flash 105 on the standard milk bottle, so that the handling of the bottles will not tend to dislodge the lip cover. If a strengthening rib be put on the cover, it is preferable that the same be further up nearer the top of the 110 bead where it will not be liable to finger engagement when handling the bottles in the ordinary process of delivery, but may also serve the purpose of means for readily dislodging the edge of the cover for the ultimate opening of the bottle when in the hands of the consumer. 115

While variations in design, dimensions, as well as the method of production are within the purview of my invention, what I claim and desire to secure by Letters Patent is:

1. A bottle closure unit comprising a holding cap and a lip cover hermetically sealed on the top surface thereof close to its edge, said cover portion being formed of paper having its outer edge the exact diameter of the intended bead surface contact with the initial tension in the paper and remainder of the cover portion bent and folded inwardly to conform to the desired 130

cover shape with radially inward extending margin pressed to a form for union with the cap top surface.

2. In a bottle closure a bottle lip protector adapted to be held to the bottle top by a sealing cap, formed from a strip of paper of an initial diameter corresponding to the intended edge contact of the protector with the bottle bead and having opposite edge 10 of said strip and the body portion folded radially inward to conform to the desired bead covering shape with a reentrant portion to extend into the bottle neck wall and an inner edge with the surplus of material 15 pressed flat and united to the top surface of the sealing cap.

3. A method of making a unit bottle closure in which a strip of paper is formed into circular or cylindrical shape of a diameter equal to the desired maximum rim 20 of the lip protecting portion of the closure and with the major portion thereupon folded inwardly and pressed to conform to the desired lip protector contour and then 25 attaching the inner constricted edge of said strip to the top surface of a sealing and holding disc.

4. A method of forming a bottle-lip protecting hood in which a strip of paper is 30 wound into cylindrical form and united to provide an edge inextensible to the extent of the initial tensile strength of the paper, thereupon folding or crowding the ribbon away from one edge inwardly to form converging sides and thereupon pressing the inwardly folded portion of the ribbon into a contiguous curved lip portion and a flat inwardly projecting rim.

5. A method of producing a bottle closure 40 having a sealing cap and a cover in which one or more plies of paper are united to a circular formation with a maximum diameter of paper in its initial state of tension equal to the desired maximum diameter of 45 the cover portion of the closure, including a weakening of the other edge of the circularly disposed paper unit, and pressing the weakened portion and the body of the paper

into converging formation with a final compressing of the paper into the finished article of a bottle-lip protecting cup portion with a contiguous radially inward extending flat rim and securing said flat rim to the top surface of the sealing cap. 50

6. A method of making a bottle closure having a sealing and holding cap, in which a lip protecting cover is made of paper with its maximum diameter of rim equal in length to the outer diameter of the bottle bead in the initial length and tensile 60 strength of finished paper and with the adjacent paper stock folded inward to the desired conformation terminating in an inner border sealed to the top of the holding cap and having a circular stiffening bead 65 formed on the skirt of the protector parallel with but separated from the inextensible edge.

7. A lip-protecting cover for a bottle closure consisting of a short cylindrical formation of paper in one or more plies having one edge of an initial circumference corresponding to the final maximum circumference of the cover edge and with the other edge fluted to contract the same and thereafter pressed into the desired form of finished article. 70

8. A lip-protecting cover for a bottle closure comprising a ribbon of paper formed cylindrically of one or more plies, one edge thereof made inextensible of the size of the proposed finished protecting outer edge and having its outer edge slashed or notched to eliminate a surplus of material in the formation of the protector and having the edge of material and the body of the ribbon formation pressed inwardly to form a contiguous inwardly curved lip-cover merging into a flat inner serrated rim and a holding cap attached to the under side of said inner rim 80 immediately adjacent its periphery. 85

In witness whereof, I have signed my name to this application this 30th day of August, 1926.

WILLIAM PATRICK HENRY.
